(57) **CLAIM**

The ornamental design for a four finger hair clip, as shown and described.

DESCRIPTION

FIG. 1 is a rear perspective view of the four finger hair clip showing my new design;
FIG. 2 is a front elevation view of the four finger hair clip;
FIG. 3 is a bottom plan view of the four finger hair clip;
FIG. 4 is an exploded view showing the two clipping element, the torsion spring and the pin separately for convenience of illustration;
FIG. 5 is a front perspective view of the four finger hair clip;
FIG. 6 is another front perspective view of the four finger hair clip in an open configuration;
FIG. 7 is a left elevation view of the left clipping element in FIG. 4 shown separately for convenience of illustration;
FIG. 8 is a right elevation view of the left clipping element of FIG. 4 shown separately for convenience of illustration;
FIG. 9 is a left elevation view of the right clipping element of FIG. 4 shown separately for convenience of illustration;
FIG. 10 is a right side perspective view of the right clipping element of FIG. 4 shown separately for convenience of illustration;
FIG. 11 is a rear bottom perspective view of the four finger hair clip;
FIG. 12 is a bottom plan view of the four finger hair clip in an open configuration;
FIG. 13 is a top plan view of the four finger hair clip in a closed configuration;
FIG. 14 is a top perspective view of the four finger hair clip in an open configuration;
FIG. 15 is a front bottom perspective side view of the four finger hair clip in an open configuration; and,
FIG. 16 is another perspective view of the four finger hair clip shown in use; the broken lines depicting environmental structures are for illustrative purposes only and do not form part of the claimed design.
